[57] CLAIM

The ornamental design for a ventilated sports goggles,
substantially as shown and described.

DESCRIPTION

FIG. 1 is a front-elevational view of a ventilated sports
goggles embodying my new design;

FIG. 2 is a bottom-plan view of the goggles of FIG. 1;

FIG. 3 is a rear-elevational view thereof;

FIG. 4 is a top-plan view thereof;

FIGS. 5, 6 and 7 are top-plan views of further embodi-
ments of the design, it being understood that the em-
bodiments shown in FIGS. 5, 6 and 7 differ from the
first embodiment only in the configuration of the top
ribs; and

FIG. 8 is a side view of the goggles.
